MANUFACTURE AND ATTACHMENT OF
BUTTONSWilliam L. Walker, Detroit, Mich., assignor to
Universal Button Fastening and Button Com-
pany, Detroit, Mich., a corporation of Michigan

Application May 19, 1942, Serial No. 443,667

10 Claims. (Cl. 79—1)

This invention relates to the manufacture and attachment of buttons and similar fastening means, and among other objects aims to provide an improved and simplified method and means for forming and attaching buttons or the like with the design or insignia on the button top in upright or predetermined position.

The nature of the invention may be readily understood by reference to one illustrative embodiment thereof shown in the accompanying drawing.

In said drawing:

Fig. 1 is a plan view, diagrammatic in character, showing the method and means for assembling a button;

Fig. 2 is a fragmentary sectional elevation taken on the plane 2—2 of Fig. 1;

Fig. 3 is a bottom plan view of a button on its discharge from the assembly mechanism;

Fig. 4 is a plan view of orienting mechanism for orienting the design on the button with respect to the garment to which it is to be attached;

Fig. 5 is a longitudinal section, on the plane 5—5 of Fig. 4, of the aforesaid mechanism showing the element which arrests rotation of the button;

Fig. 6 is a sectional elevation of the button during the attaching operation; and

Fig. 7 is a similar sectional view showing the button completely attached.

Buttons of the character herein referred to are known in the trade as registered buttons, by which is meant buttons (or similar fastening means) designed to permit automatic attachment with the design or insignia on the button top in upright or predetermined position. Heretofore the disadvantages of the manufacture and attachment of buttons of this character have generally outweighed its advantages; and an object of the present invention is to eliminate the major disadvantages.

The invention is here illustrated in connection with the attachment of a button by a double prong fastener 10. It is not necessary here to detail the advantages arising from the use of a double pronged attaching fastener, but such use involves additional problems of attachment (not involved in the use of a single prong fastener) since both fastener and button must be relatively oriented. The illustrative button 11 is a so-called open top button, by which is meant a button having a central opening 12 in its top which permits the entry into the interior of the button of the attaching die 13 whose concave

extremity 14 functions to upset or curl the fastener prongs. In closed top buttons it is the practice to incorporate in the interior of the button a die which has the function of upsetting the fastener prongs. The button comprises a top or shell 15 generally made of thin sheet metal whose margins 16 are bent or crimped around the margins of the collet or shank of the button. The button top carries some decorative design or insignia 18 which may comprise the trade-mark of the manufacturer of the garment to which the button is attached. The collet also is generally of sheet metal.

To attach the button in registered or oriented position, it is necessary to provide means, which advantageously are incorporated in the attaching apparatus for axially rotating the button until its design or insignia 18 occupies a predetermined position. Attachment with a double pronged 15 fastener or other fastener which is not symmetrical in all axial positions has additionally required that the collet of the button be registered or oriented relative to the design on the shell prior to completion of assembly so as to occupy 20 the proper position relative to the fastener prongs in the attaching apparatus.

According to the illustrative method, the necessity for orienting the collet is eliminated and assembly of the button is thereby substantially simplified. As here shown the shells 15 are provided with a deformation in this case comprising a projecting lip 19 formed in the margin 16 of the shell. This deformation is formed simultaneously and generally by the same dies which 30 emboss the design 18 in the shell and therefore occupies a predetermined position relative to the design. Such deformation provides the means by which the design on the shell may be located in a predetermined position in the assembly mechanism. In the present instance, the shells are deposited from a slide or chute 20 into openings 21 in the assembly mechanism here represented by a rotating dial 22. The openings 21 are of a size to receive and center the shells and 35 are provided with a correspondingly shaped recess 23 for the lip 19 of the shell to hold the shell against angular displacement. In this case the shells are deposited upside down, that is, with the inside of the shell uppermost in the openings 21, each shell having previously been oriented so that the lip 19 registers with the recess 23 of the opening. The dial 22 is periodically rotated by an amount representing the angular distance between successive openings 40 21 in the direction indicated by the arrow 24

bringing the openings successively to the station 25 at which the collets 17 are deposited upside down inside the shell. Such collets may advantageously simply slide into position down a chute 26.

Further travel carries the shell and collet to the closing apparatus here represented by upper and lower dies 27 and 28 which function to crimp or close the margin 16 of the shell around the margin of the collet and at the same time to obliterate or eliminate the lip of the deformation 19 in the shell. In the present instance dies 27 and 28 are vertically reciprocable and register with the successive openings 21 at the station 29. The stationary plate 30 on which the dial rotates and which functions to prevent the buttons from dropping through the openings 21 is provided with an opening 31 through which lower die 28 may pass to raise the button from the dial for the closing operation. At some stage in said closing operation the collet is pierced with an eccentric or non-circular opening 32 for receiving one of the fastener prongs. In the present case such opening is generally of semi-circular shape and is formed by piercing die 33 which penetrates the bottom 34 of the collet as the latter is confined inside upper die 27.

The successive openings 21 register with a discharge opening 36 in the plate 30 through which the completed button falls.

In the completed button the eccentric or non-circular opening 32 in the collet has a predetermined location relative to the design or insignia 18 on the button top and is utilized to orient the design properly in the attaching machine. The opening 32 may be either eccentric or of such non-circular shape as to serve as a key in locating the design on the button top in predetermined position. For attachment with a double prong fastener the opening is both eccentric and non-circular. The attaching machine incorporates means for axially rotating the button and means for orienting the button in proper position by entering the opening 32 and arresting further rotation. Attaching means of this character are illustrated in Clark Patent No. 1,798,970 and in the co-pending Hansen and Bowen application, Serial No. 299,586, Patent No. 2,292,223, issued August 4, 1942. Each of such machines embodies an orienting fork for entering the opening in the collet of the button when the latter has been rotated to a predetermined position to arrest further rotation. In the present case, the collet is pierced with only one opening and the fork is correspondingly formed with only a single prong of proper eccentricity or in this case of generally semi-circular section so located as to enter the opening 32 in the collet when the button has been rotated to its proper position. An orienting fork of this character together with the orienting mechanism of said Hansen and Bowen application is illustrated in Figs. 4 and 5. The details of the orienting mechanism are fully described in said Hansen and Bowen application, and it will, therefore, here be sufficient to point out that the orienting fork 37 is provided with an extremity 38 of generally semi-circular section of such shape as to enter the opening 32 when rotation of the button in the orienting mechanism carries the opening 32 therein into registry with the fork. In that position the spring 39 rotates the fork about its pivot 40 and causes the extremity 38 to enter the opening 32.

and arrest further rotation of the button. In such oriented position the button is moved to attaching position as described in said Hansen and Bowen application.

5 The attaching mechanism is illustrated only generally in Figs. 6 and 7. Unnecessary details have been omitted to simplify and clarify the illustration. Details of similar attaching mechanisms are illustrated in said Clark patent and in said Hansen and Bowen application. The attaching machine functions also to locate a fastener 43 in attaching position with the fastener prongs 41 and 42 located in predetermined position. At the beginning of the attaching operation the lower die 43 on which the fastener rests raises the same and causes its prongs to pierce the fabric 44 to which the button is to be attached. Simultaneously the attaching mechanism carries the button down into contact with the cloth. The movement of the button and fastener towards each other causes the prong 41 to pierce the bottom 34 of the collet forming therein an opening 46, and the other prong 42 to enter the opening 32 in the collet. Continued movement brings the prongs into engagement with the upsetting die surface 14 and curls the same in opposite directions tightly around the intervening bar 45 of the collet. In this connection it should be noted that the margins of the opening 32 as well as those of the opening 46 pierced by the fastener prong are bent or curled inwardly and serve to stiffen the bottom of the collet and particularly the intervening bar 45. The fastener prongs are sufficiently sturdy so as to be capable of piercing the metal of the collet. Preferably the prongs are tapered for increased strength and rigidity.

After attachment the attaching dies recede, thereby freeing the garment with its attached buttons.

40 It will be apparent from the foregoing that the inventive method simplifies assembly of the button and eliminates the necessity for special orienting stops or projections on the button heretofore necessary for orienting the button in attaching position, utilizing simply a non-circular or eccentric opening in the collet which subsequently serves to receive a fastener prong. When attached in upright position by a double prong fastener, subsequent rotation of the button out of upright position is impossible.

45 Obviously the invention is not limited to the details of the illustrated method and apparatus since these may be variously modified. Moreover it is not undesirable that all features of the invention be used conjointly in different combinations and sub-combinations.

50 Having described my invention I claim:

1. The method of orienting buttons and attaching them by a double pronged fastener which comprises providing a button with a single eccentric opening in the button collet in predetermined relation to a surface of the button, then by means of said opening orienting the button with respect to the double prongs of a fastener, then causing the prongs of the fastener to enter the button, one passing through said opening and the other piercing the collet, and then upsetting the prongs inside the collet.

55 2. The method of orienting buttons and attaching them with the design on the button top in predetermined position which comprises providing a button having in its collet a single fastener prong opening non-circular in shape and eccentrically located and having a predetermined po-

sition relative to said design, orienting the button by means of said opening, and then attaching the button by means of a double pronged fastener, one fastener prong passing through said opening and the other piercing the collet.

3. The method of orienting buttons and attaching them with a design in the button located in predetermined position which comprises providing a button top carrying the design and an attached collet having an opening so that the opening occupies a predetermined position in relation to the design, orienting the button by means of said opening, and attaching the same by a double pronged fastener with one prong passing through said opening and the other piercing the collet adjacent thereto, and curling the fastener prongs about the portion of the collet between the prongs.

4. A button of the character described comprising in combination a button top having a design thereon, and an attached button collet having in its base an eccentric single non-circular fastener prong receiving opening having a predetermined position relative to said design so that, in attaching the button, the opening is used as an orienting medium.

5. A button of the character described comprising in combination a button top having a design thereon, and an attached button collet having in its base an eccentric single fastener prong receiving opening which is asymmetrical relative to said design and adapted for use in orienting the button for attachment.

6. A button of the character described comprising in combination a button top having a design thereon, and an attached button collet having in its base a single eccentric non-circular fastener prong receiving opening having a predetermined position relative to said design for use in orienting the button for attachment.

7. Button apparatus comprising in combination a button holder having a circular recess for holding a button of circular section, piercing mechanism including a single piercing tool located eccentrically with said recess and adapted to form a single fastener receiving hole through the under part of the button and means for locating a button with a design on its top in said recess

with the design in a predetermined relation relative to said piercing tool, said piercing tool operating to form an eccentric fastener receiving hole in the button in a predetermined position relative to the design on the top, whereby the said hole may be employed to orient the design on the button for attachment of the button to a garment or the like.

8. Button apparatus for buttons having a design on their tops comprising in combination means for holding a button top with the design thereon located in a predetermined position in the holding means, means for placing a collet in the top while the latter is in the holding means, and piercing mechanism including a single piercing tool located in a predetermined position with respect to the design on the button top in the holding means, said tool being adapted to form a single hole in the said collet in a predetermined position with respect to the design on the button top.

9. Button apparatus for buttons having a design on their tops comprising in combination means for holding a button top with the design thereon located in a predetermined position in the holding means, means for placing a collet in the top while the latter is in the holding means and piercing mechanism including a single piercing tool of non-circular section located in a predetermined position with respect to the design on the button top in the holding means, said tool being adapted to form a single non-circular hole in the said collet in a predetermined position with respect to the design on the button top.

10. The method of orienting buttons and attaching them by a double pronged fastener which comprises providing a button including a collet and a top with a design on said top and a single eccentric opening in the collet in predetermined relation with the design on the top, then by means of said opening orienting the button with respect to the double prongs of a fastener, then causing the prongs of the fastener to enter the button, one passing through said opening and the other piercing the collet, and then upsetting the prongs inside the collet.

WILLIAM L. WALKER.
